UNITED STATES PATENT OFFICE

2,328,095

BATTERY HOLDER

Mary C. Phillips, Malden, Mass.

Application November 14, 1941, Serial No. 419,140

2 Claims. (Cl. 224—5)

The main purpose of the present invention is to provide a convenient holder and support for the electric battery which constitutes a part of apparatus furnished as an aid to hearing of deaf persons. Such batteries have substantial size and weight and their satisfactory stowage in the clothing of the user offers somewhat of a problem, particularly to those whose clothing is not well equipped with pockets. But even where pockets are provided, the weight of a battery placed in one frequently causes unsightly sagging of the garment.

Having before me the problem of enabling women, particularly, to carry batteries of this character conveniently, without imposing weight uncomfortably, or impairing the lines of their clothing or encumbering their hands, I have devised a holder or support which may be suspended from a belt, girdle or foundation garment and otherwise held close to the body so as not to swing, and includes a pocket in which a battery may be placed and confined.

Although I have here specified one purpose and use of the invention, I wish to make it clearly understood that I am not limited to such use, but claim protection for the novel principles and characteristics of the article hereinafter described, and all substantial equivalents thereof, for all the purposes and uses to which it may be put. Hence the term "battery holder," by which the article is called in the title of this patent and in the following description, is to be construed as including equivalent holders or supporters when designed and used for carrying other things than hearing aid batteries and whether applied to the person in the manner herein shown or otherwise.

One embodiment of the invention, which at present I consider preferable to others, is shown in the accompanying drawing, in which—

Fig. 1 is a perspective view of the portion of a person's body to which this embodiment of the invention is designed to be applied, showing the holder applied thereto;

Fig. 2 is a front view of the holder removed from the person;

Fig. 3 is a similar view of the pattern for the fabric piece which forms the main or back sheet of the holder; showing by dotted lines the manner in which the piece cut according to this pattern is folded in being made up into the finished article;

Fig. 4 is a similar view of the pattern for the front member of the pocket, showing by dotted lines the manner in which the piece cut to that

pattern is folded in being assembled with the back sheet;

Figs. 5, 6, 7 and 8 are relatively enlarged sectional views taken on lines 5—5, 6—6, 7—7 and 8—8, respectively, of Fig. 2.

Like reference characters designate the same parts wherever they occur in all the figures.

The holder here shown consists of a generally triangular backing sheet or piece *a* of flexible fabric and a front piece *b* also of flexible fabric, of smaller dimensions, stitched to the piece *a* in a manner to form a pocket wherein an oblong article of substantial thickness, such as the battery commonly provided with hearing aid apparatus may be contained. The fabric used for these pieces is preferably a closely woven smooth textile fabric light in weight, and the pieces are made of two or more plies each to give ample strength. The piece *b* is applied to the central area of the backing piece *a* and is stitched thereto along its opposite side edges *c* and *d* from the bottom ends thereof to the points *c'* and *d'*, and along the bottom edge *e*, leaving its upper end unattached throughout the full width between said points *c'* and *d'*. The piece *b* is wider than the prescribed width of the pocket and its side edges are stitched to the backing piece on parallel lines nearer together than the width of the piece; and, in stitching, the lower ends of the lateral margins of the piece are folded under, as indicated by dotted lines in Fig. 4 and as shown at *f* and *g* in the sectional views, Figs. 7 and 8, and secured by the seams which run parallel with the edge *e*. This construction provides fullness in the pocket to receive a thick article like a battery without materially bulging the backing piece.

The upper end of the front piece is cut with a taper and with notches *h* and *i* in the opposite edges forming a tongue *j*. Below these notches the side margins of the piece are folded inward and stitched to the adjacent body part of the piece to reinforce the base of the tongue. The tongue is passed through the slot of a flat hook or clasp *k* and stitched down to the back of the piece *b*. Said clasp cooperates with a strap later described to support the outer wall of the pocket and secure the inserted article.

A suspension strap or suspender *l* is secured to the uppermost angle of the backing piece on the outside thereof and has a downward extension *l'* equipped with a loop *m* into which the hook *k* may be passed. The strap *l*, preferably made of elastic webbing, is extensible in length, being doubled over and having attached to its end a

clasp *n* which embraces the forward stretch of the doubled strap and is adapted to be clamped at any point along the length thereof. A safety pin or equivalent fastener *o* is located in the bight of the folded strap, whereby the strap may be made fast to an article of the wearer's clothing, such as the waist band of a garment, a belt, a girdle, etc.

The opposite lower corners or angles of the back piece are at substantially equal distances from the topmost angle or apex, and to one of them is secured a strap *p* and to the other a flattened ring *r* with a protective tab *s* back of it. The strap *p* is of like construction to the strap *l*, passing through a slot in a flat hook *t* and doubled back, with a clasp *u* on its extremity to grip the standing part of the strap and adjust the effective length of the strap between the hook *t* and the corner of the backing piece to which the strap is secured. Strap *p* is adapted to be passed around the leg of the wearer and the hook *t* to be then engaged with the ring *r*.

When applied to the use specified in the introductory part of this specification the fastener *o* is attached to a garment of the wearer, such as the girdle *w* shown in Fig. 1, at the side of the hip or thigh and at a height such as will locate the pocket at a convenient distance above the wearer's knee. The strap *p* is passed around the wearer's leg and hooked into the ring *r*, having been adjusted to a length which will confine the holder closely to the leg without being tight enough to be uncomfortable. The battery, shown in dotted lines in Figs. 1 and 5, is placed in the pocket and the hook *k* is caught into the ring *m*. It may be noted at this point that the lower corners of the backing piece *a* are made with excess width and the edges *a¹* and *a²* are folded under so as to bring the outline approximately to that indicated by the dotted lines *a³* and *a⁴*, and are sewed fast. This formation causes the side edges of the holder to lie close against the wearer's leg notwithstanding the tendency of the weight of the battery to pull them away.

It will be apparent from the foregoing description that the holder is easily adjusted and practical. It is comfortable to wear, and by virtue of the manner in which it is applied to the body, it makes the weight of the enclosed battery practically inappreciable to the wearer. The support afforded by the outer wall of the pocket, the strap extension *l'* and hook *k*, assists greatly in diminishing the apparent weight.

This device is adapted to be made either right or left by reversing the positions of the leg strap *p* and ring *r*.

It may be noted that the thickness of the material as shown in the sectional views of this drawing is greatly exaggerated for clarity. Actually the fabric of the specimen chosen for illustration here is hardly thicker than the width of the lines of the drawing. But of course any suitable fabric of any suitable thickness, weight and strength may be used according to the ser-

vice for which a particular embodiment of the invention is intended.

What I claim and desire to secure by Letters Patent is:

1. A container for supporting, on the person, an electric battery comprising a backing sheet of flexible material having a wide base and side edges converging upwardly to an apex, a suspender secured to said apex extending upwardly therefrom, means connected with the upper end of said suspender for attaching the same to a garment of the wearer, an extension on said suspender extending downward from the connection of the suspender with said apex in front of the base member, a strap and a cooperative connector secured respectively to the opposite base corners of the backing member arranged to cooperate with the backing member in surrounding a leg of the wearer, a front piece narrower at its lower end than the base portion of the backing piece stitched at its bottom and side edges to the latter to form a pocket adapted to receive a battery, and having a free upper end with side edges converging upwardly toward the median line, a fastening member secured to the upper extremity of said front piece, and a co-operating fastening member secured to said suspender extension at a height suitable for engagement with the first named fastening member and to transmit to the suspender the stress imposed on the front piece by the weight of a battery contained in the pocket.

2. A holder for supporting on the person the battery of an aid to hearing apparatus, comprising a backing piece of flexible fabric, a front piece secured at side and bottom edges centrally to the backing piece, and being of greater width than the distance between the lines at which its side edges are secured to the backing piece to provide a pocket with sufficient fullness to contain such a battery, the base of the backing piece extending at both sides beyond the bottom of said pocket, and its upper extremity extending above the top of the pocket, and the backing piece being of triangular outline with side edges converging from the lower corners to a central apex at its top, a strap connected to one of said base corners having a coupling member at its end, a complementary coupling member connected to the other of said base corners, said backing member, strap and coupling members cooperating to surround a leg of the user of the container and to hold the container close against such leg, a suspender fastened to the apex of the backing member and extending upwardly therefrom, means connected with the upper extremity of the suspender for attachment to a portion of the clothing of the user, and means for coupling the upper extremity of the front member to said suspender when a battery is contained in the pocket, constructed and arranged to transmit to the suspender the tension created in the front member by the weight of the battery.

MARY C. PHILLIPS.
